HANDLE-STOP FOR RAILWAY CAR SIDE DOORS

Arthur E. Small, Chicago, Ill., assignor to Railway Metal Products Company, Chicago, Ill., a corporation of Delaware

Application July 18, 1930. Serial No. 468,880

5 Claims. (Cl. 292—246)

This invention relates to a railway box car having a door opening in a side wall thereof and a slidable door arranged to close the opening. Such a door is supported by hangers from a track positioned above the door or by brackets slidably engaging a track positioned below the door or by brackets mounted on the car below the door, which engage a track secured to the door. Such hangers and brackets are usually provided with anti-friction rollers.

The object of the invention is to mount a handle upon the door so that when being used to move the door the handle clears the brackets and allows free movement of the door, but when the door is in any one of several predetermined positions the handle, upon release, falls by gravity into engagement with one of the brackets to retain the door in such predetermined position; for instance, the engagement of the handle with the bracket may be used to retain the door in a closed position; in full open position or in partially open and partially closed position, the last mentioned position being used when the car is transporting perishable freight, such as fruits or vegetables, and provides a certain amount of ventilation in the car.

In the drawing:

Fig. 1 is a diagram showing the relation of the handle and brackets in closed and open position of the door.

Fig. 2 shows the handle, one of the brackets and associated parts of the car.

Fig. 3 is a section on line 3—3 of Fig. 2.

Fig. 4 is similar to Fig. 2 showing the handle in another position relative to one of the brackets.

In the drawing the usual parts of the car are shown, such as side sill 1; floor support 2; flooring 3; door 4; door opening 5; door lower stiffener 6 and door lock 7.

The drawing shows a vertical car wall having a door opening therein and a horizontally slid-able door 4 to close the opening; wherein the brackets 10, 11, 12 and 13 are mounted upon the side sill 1 below the door and support the door in case of failure of the usual supports of the door and furthermore hold the door close to the car by engaging the depending flange 15 on the lower stiffener 6. The U-shaped handle comprises a central grab portion 22 and spaced apart end portions 17. The end portions are each pivotally mounted upon the car by brackets 18 to swing only in a plane substantially normal to the car. When in elevated position, as shown in dotted lines in Fig. 3, the handle

clears all the brackets and allows free movement of the door. This position is the natural one for the handle to assume when an operator is moving the door, either from a loading platform or from the ground. When released the handle assumes the lowered position shown in solid lines in Figs. 2, 3 and 4. When in such lowered position a portion 17 of the handle engages one of the walls 20 of one of the brackets and prevents the door from moving in one direction, as shown in Fig. 4. When it is desired to prevent the door from moving in either direction the handle straddles a bracket, as shown in Fig. 2, or may be designed to rest between portions of the bracket. When it is desired to move the door the handle is grabbed by the operator and automatically moved to the elevated position so that it clears the brackets. After the door is fully closed the handle automatically drops to the position shown in Fig. 1 and prevents the door from moving toward an open position. The usual front stops on the car body prevent the door from moving in the opposite direction. When it is desired to retain the door in a full open position a similar relation is established between the handle and one of the other brackets (11).

It may be desirable to position one of the brackets so that the handle straddles it to retain the door in completely closed position. A plurality of handles may be used if desired to hold the door in various degrees of openness. The bracket shown is provided with spaced apart walls 20 and the handle is bent so that the grab portion 22 has clearance all around it; furthermore, the walls 20 of the bracket are slightly deflected at their upper part 24 to guide the handle into position.

The accompanying drawing illustrates the preferred form of the invention, though it is to be understood that the invention is not limited to the exact details of construction shown and described, as it is obvious that various modifications thereof, within the scope of the claims, will occur to persons skilled in the art.

I claim:

1. In a railway car, a handled stopping device for use with a horizontally slid-able door, said device comprising a bracket mounted upon the car below said door having spaced apart walls, and a U-shaped handle comprising a central portion and spaced apart end portions, said end portions each pivotally mounted upon the door to swing only in a plane substantially normal to the door, said bracket being positioned in the path of movement of said handle,

- whereby when the handle falls by gravity to lowered position, said end portions engage said walls respectively and prevent horizontal movement of the door in either direction but when said handle is in elevated position it clears the bracket and allows free movement of the door. 4. In a railway car, a handled stopping device for use with a horizontally slidable door, said device comprising a bracket mounted upon the car below said door having spaced apart walls, and a U-shaped handle comprising a central portion and spaced apart end portions, said end portions each pivotally mounted upon the door to swing only in a plane substantially normal to the door, said bracket being positioned in the path of movement of said handle, whereby when the handle falls by gravity to lowered position, said end portions engage said walls respectively and prevent horizontal movement of the door in either direction but when said handle is in elevated position it clears the bracket and allows free movement of the door, said bracket so positioned that when the handle engages the bracket as specified the door is retained in closed position and another such bracket so positioned that when the handle engages said last named bracket as specified the door is retained in open position. 5. In a railway car, a handled stopping device for use with a horizontally slidable door, said device comprising a bracket mounted upon the car below said door having spaced apart walls, and a U-shaped handle comprising a central portion and spaced apart end portions, said end portions each pivotally mounted upon the door to swing only in a plane substantially normal to the door, said bracket being positioned in the path of movement of said handle, whereby when the handle falls by gravity to lowered position, said end portions engage said walls respectively and prevent horizontal movement of the door in either direction but when said handle is in elevated position it clears the bracket and allows free movement of the door, said central portion of the handle being positioned adjacent said clear space when the handle is in lowered position, whereby said central portion may be used as a handle. 3. In a railway car, a handled stopping device for use with a horizontally slidable door, said device comprising a bracket mounted upon the car below said door having spaced apart walls, and a U-shaped handle comprising a central portion and spaced apart end portions, said end portions each pivotally mounted upon the door to swing only in a plane substantially normal to the door, said bracket being positioned in the path of movement of said handle, whereby when the handle falls by gravity to lowered position, said end portions engage said walls respectively and prevent horizontal movement of the door in either direction but when said handle is in elevated position it clears the bracket and allows free movement of the door, said bracket so positioned that when one of said end portions engages one of said walls the door is retained in closed position and when each of said end portions engages one of said walls respectively the door is retained in partially open position.
